UNITED STATES PATENT OFFICE.

CHARLES E. LE PAGE, OF BROOKLYN, NEW YORK.

REFUSE VEHICLE.

Application filed June 11, 1927. Serial No. 198,243.

My invention relates to improvements in refuse collecting and delivering vehicles, particularly of the self-propelled class, as instanced in prior Letters Patent issued to me 5 June 22, 1920, No. 1,344,047, to which reference is to be made.

In using the specific form of vehicle shown in said patent, the ashes or other refuse is dumped from the scattered cans or containers 10 into a low hung hopper, of which one is on each side of the vehicle, and from each hopper the refuse is carried upward and rearward by an endless conveyor, operated by the vehicle driving mechanism, through a chute opening 15 into a dumping body, also operated by the vehicle driving mechanism.

My present invention has for its objects among others, to improve the construction and operation of the conveyor, its enclosing 20 chute, and the dumping body, and the means for operating the conveyor and the dumping body from the vehicle driving mechanism, and to prevent the clogging of the conveyor in its chute.

To this end my invention comprises flights of novel construction, alternated with the buckets on the conveyor chains; shields beneath and to the rear of the ascending buckets and flights to support the same and hold the 25 refuse in the buckets and flights; drums around the conveyor sprocket wheels and fitting the chutes and hoppers to cooperate therewith in leading the refuse from the hoppers to the conveyors; a forward constriction 30 and extension of the body between the conveyor chutes to increase the capacity of the body; improved means for operating and controlling the operation of one or both conveyors from the vehicle driving mechanism; 35 and improved means for operating and controlling the operation of the dumping body from the vehicle driving mechanism.

In order that my invention may be fully understood, I shall first describe in detail the 40 mode in which I at present prefer to carry the invention into practice and then particularly point out the various features of the invention in the claims.

Reference is to be had to the accompanying 45 drawings forming part of this application in which corresponding parts are designated by the same number in all the figures.

Figure 1 is a side, partly sectional elevation of a self-propelled refuse handling vehicle embodying my invention. 55

Figure 2 is a cross-section of the conveyor chute.

Figure 3 is a rear end elevation of the same, parts being in section and parts being 60 omitted.

Figure 4 is a plan view of the same.

Figure 5 is a detail view of the conveyor control.

Figure 6 is an enlarged plan view of part of the conveyor control mechanism. 65

Figure 7 is a sectional view of the conveyor control mechanism on the line 7-7, Figure 6.

In the embodiment of my invention thus illustrated, 7 designates the frame of the vehicle mounted on wheels 8 and driven by a 70 motor in the usual manner.

9 designates the usual longitudinal drive shaft of the vehicle, shown in section in Figure 3 and indicated in dotted lines in Figure 4. 10 designates the transmission, which together with the chassis and vehicle driven mechanism here illustrated is that of the ordinary Mack truck. 11 designates the ordinary standard one-speed Mack power take-off, 75 operated through the shaft 12, from the transmission 10.

From the drive shaft 13 of the power take off 11 and thus from the vehicle drive shaft 9, I prefer in this example of my invention to operate and control the conveyors 14, 15 in 80 their respective chutes 16, 17 as follows:

The conveyor chains 18, 19 at their lower ends run around sprocket wheels 20, 21, which are fixed axially on aligned but independent transverse shafts 22, 23, which turn in suitable bearings on the frame 7.

The inner ends of the shafts 22, 23, as best shown in Figures 3 and 4 are connected by flexible couplings 24, 25 with axially aligned short shafts 26, 27, mounted in ball-bearings 95 28, 29, in a casing 30 fixed on the frame.

The inner ends of the short shafts 26, 27 are borne and spaced yieldingly apart by a spring-pressed plunger bearing 31, working in a socket in the end of the shaft 26, and bearing against the end of the shaft 27. 100

On inner annular bearings 32, 33, surrounding the shafts 26, 27 and in outer annular bearings 34, 35, mounted within the casing 30,

is mounted to turn the hub 36 of a worm wheel 37, in which the hub is fixed by pins 38 as shown. The worm wheel 37 is driven by a worm 39 fixed on a shaft 40, which is in turn driven from the power take off shaft 13, by a chain 41 (Figure 3) and sprocket wheels 42,43.

5 The worm wheel 37 is thus driven by the motor and drive shaft 9 of the vehicle.

In opposite ends of the worm wheel hub 36 10 are formed female clutch sections 44, 45 (Figure 7) adapted to be engaged and disengaged simultaneously or alternately by corresponding male clutch sections 46, 47, keyed so as to be compelled to turn with but to slide axially 15 on the respective short shafts 26, 27. The male clutch sections 46, 47 are formed with annularly grooved clutch collars 48, 49, which are engaged loosely and can be shifted axially by corresponding segments 50, 51 of 20 clutch plates 52, 53, mounted to slide in guides 54, 55 in the casing 30 parallel to the axis of the clutch shafts 26, 27.

By properly shifting the clutch plates, 52, 25 53 in their guides, the main driving worm wheel 37, can thus be clutched to either or both the conveyor operating shafts 26, 27, or unclutched from both said shafts so as to operate either or both conveyors 14, 15, simultaneously or neither of them.

30 To operate the clutch plates 52, 53, and thus the conveyors 14, 15 selectively as desired, I, in this example of my invention fix anti-friction cam-studs or followers 56, 57 on the clutch plates to ride in cam slots 58, 59, in a cam-plate 60, and the cam-plate 60 is mounted to slide transversely to the shafts 26, 27 in a guide 61 formed in the casing 30.

The cam slot 58 has a terminal part 62 at 40 an angle to the motion of the cam, a medial part 63 in line with said motion and a terminal part 64 at an angle, as shown in Figure 6.

The cam slot 59 has a terminal part 65, in line with the motion, a medial part 66 at an angle, and a terminal part 67, parallel to but 45 inside the opposite terminal part 65.

The cam-plate 60 is shown in Figure 5, operated by a link 68 and adjustable handle lever 69.

With this construction, when it is desired 50 to render both conveyors 14, 15 inoperative the cam-plate 60 is moved to the position shown in Figure 6, thus disengaging both clutch sections 46, 47, from the driving worm wheel 37.

55 To operate both conveyors 14, 15, simultaneously, the cam-plate 60 is moved to bring the cam-followers 56, 57, into the ends of the cam slots 64, 67, thus engaging both clutch sections 46, 47 with the worm wheel 37.

60 To operate the conveyor 14 but not the conveyor 15, the cam-plate is moved to bring the cam followers 56, 57, into the ends of the slots 58, 59, thus engaging the clutch section 46, but leaving the clutch section 47 disengaged.

To operate the conveyor 15 but not the conveyor 14, the cam-plate 60 is moved to bring the cam follower 57 into the beginning of slot 67, and the cam follower 56 into the end of the slot 63, thus engaging the clutch section 70 47, but leaving the clutch-section 46 disengaged.

The conveyors 14, 15 can thus be conveniently controlled from the driver's seat as indicated in Figure 1, showing the position of 75 the control handle 69.

To improve the effectiveness of the conveyors 14, 15, and prevent their being clogged by the refuse, I alternate with the buckets 70 on the sprocket chains 18, 19, flights 71 secured on links 72 separated by links 73, from the links 74, carrying the buckets 70, and I taper the flights 71 toward their outer ends so as to automatically release the refuse which may be caught between their tapering side 85 edges and the sides of the conveyor chutes 16, 17, or the refuse receiving hoppers 75, 76, from which the chutes 16, 17 lead upward and rearward.

The buckets carry the softer or finer material and the flights the harder or coarser material.

On upper transverse conveyor shafts 82, journaled in opposite sides of the frame, are mounted loose sprocket wheels 81, around 95 which the respective conveyor chains, 18, 19, travel. On the conveyor shafts 22, 23 and 82, 82, are fixed, on opposite sides of the respective sprocket wheels 20, 21, 81, 81, drums 77, 78, having on their outer sides flanges 79, 100 80.

The inner ends of the buckets and flights are tapered to fit the peripheries and flanges of the respective pairs of drums, and the drums thus correspond to and cooperate with 105 the buckets and flights to pick up all the refuse in the hoppers and dump all the refuse, as the buckets and flights pass over the upper sprocket wheels, into the dumping body 84, through the upper chute openings 83. 110

To support the upwardly passing links, flights 71 and buckets 70, and retain the refuse therein, I fix on each chute closely beneath and to the rear of the same, an inclined shield 85 extending the distance between the lower 115 and upper drums 77, 78, and across the chute, over which the inner ends of the flights travel and by means of which they are guided. Likewise to support the downwardly passing links, buckets and flights, I fix on the rear of each chute 16, 17, a wear plate 86, extending from the chute opening 83 to the lower hopper and across the chute, over which wear plate the outer ends of the downwardly passing flights 71, travel, and by which they are 125 guided.

The inner and outer edges of the flights 71 are formed with upturned transverse shoes 87, 88, the outer lips acting as shields to scoop and retain the refuse, and also as bearings on 130

the wear plate 86, and the inner shoes 87 act as bearings on the shield 85.

The dumping body 84, has segmental upper openings 89, registering with the corresponding discharge openings 83 in the chutes 16, 17, so as to permit the dumping body to be tilted, as indicated in Figure 1 for dumping its contents.

To increase the capacity of the dumping body 84, I form it with a forward constriction and extension 90 which fits and tilts between the chutes 16, 17.

To tilt the dumping body 85 from the vehicle drive mechanism when desired to dump its contents, I arranged an ordinary screw hoist 91 beneath the same as indicated in dotted lines in Figure 4, and operate the same from a secondary drive shaft 92 through an ordinary clutch (not shown) from the power take up 11, driven by the vehicle motor.

It is evident that many changes may be made in the details of construction and arrangement herein described without departing from the boundaries of my invention which are defined by the following claims.

It is evident also that an attractive toy vehicle may be made on the general lines herein described, in which case the motor may if desired be omitted and the conveyors and dumping body operated by hand, as by cranks or hand wheels on the conveyor shafts or on any of the operating shafts.

I claim as my invention:

1. A refuse vehicle provided with receiving hoppers on both sides, inclined conveyors on both sides leading upward from the respec-

tive hoppers, separate driving shafts for the respective conveyors, a motor, and a shaft driven thereby, a double clutch section driven thereby, a separate clutch sections to drive each conveyor shaft, and means for engaging either of the conveyor driving clutch sections with and disengaging it from the double motor-driven clutch section.

2. A refuse vehicle in accord with claim 1 provided with means for engaging both of the conveyor clutch sections simultaneously with or disengaging them both simultaneously from the double motor-driven clutch section.

3. A refuse vehicle in accord with claim 1 in which the separate conveyor driving shafts are axially aligned and a yielding bearing is interposed between their adjacent ends.

4. A refuse vehicle in accord with claim 1 in which the separate conveyor driving shafts are axially aligned and the double motor driven clutch section is mounted to slide on but to turn with both conveyor driving shafts, and the separate conveyor clutch sections are mounted to slide on but to turn with the respective conveyor driving shafts.

5. A refuse vehicle in accord with claim 1 in which the means for engaging and disengaging the separate conveyor clutch sections from the motor driven clutch section, consists of a separate cam follower for each conveyor clutch section and a movable plate having separate cam-slots for the separate cam followers.

In testimony whereof I affix my signature.

CHARLES E. LE PAGE.
